FIG. III.

FIG. IV.

Inventor
LEWIS D. NELSON

By *Chappell & Carl*

Attorney, D

UNITED STATES PATENT OFFICE.

LEWIS D. NELSON, OF COLDWATER, MICHIGAN, ASSIGNOR OF ONE-HALF TO ROBERT M. NEALE, OF UNION CITY, MICHIGAN.

CONVEYER.

Application filed August 28, 1924. Serial No. 733,775.

This invention relates to improvements in conveyers.

The main objects of this invention are:

First, to provide an improved conveyer which is well adapted for the loading and unloading of cars and which may be readily set up or adapted for the particular requirement.

Second, to provide an improved portable conveyer which may be quickly set up or disassembled.

Third, to provide an improved conveyer which is well adapted for handling heavy material such as bags of cement.

Further, objects and objects pertaining to details and economies of construction and operation will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing forming a part of this application, in which:

Fig. I is a side elevation of the main unit and one of the supplementary units of my improved conveyer.

Fig. II is a plan view of the structure shown in Fig. I, the platform of the main unit and a portion of the supplementary unit being broken away.

Fig. III is an elevation looking from the right of Fig. I, one of the supplementary units being shown in position on a truck for transportation, the other supplementary units being indicated as superimposed thereon by dotted lines.

Fig. IV is an enlarged detail side elevation showing details of the conveyer and the driving mechanism.

Similar numerals of reference indicate similar parts in all of the views.

Referring to the drawing, I provide a main unit designated generally by the numeral 1 and a plurality of supplemental units designated generally by the numeral 2. Only one of the supplemental units is shown as it will be understood that these supplemental units are duplicates.

The main unit is mounted upon a truck 3 being supported thereon by uprights or

standards 4. The platform 5 of the truck 3 is extended at one side of the main unit to receive the supplemental unit. The main and supplemental units are substantially the same in structure and I use the terms "main" and "supplemental" or "supplementary" largely as a matter of convenience in description.

Each unit comprises a pair of side members 6 having hooked coupling members 7 at their ends. The coupling members at both ends of the main unit are arranged facing upwardly. The coupling members at the inner ends of the supplemental units are arranged facing downwardly while those at their outer ends are arranged facing upwardly.

The supplemental units are provided with legs 8 at their outer ends adapted to be folded for convenience in storing and handling the units. These legs when erected support the supplemental units as they are joined together.

Each unit is provided with a carrier comprising a pair of shafts 9 extending between the cross members and provided with sprocket wheels 10. The sprocket wheels carry the chains 11 having cross pieces 12 thereon. The shafts 9 are arranged so that when the units are assembled end to end one carrier delivers to the adjacent carrier.

Each shaft is provided with a pinion 13, idler pinions 14 being provided at opposite corners of each unit so that when the units are assembled they are provided with driving connections and the carriers are driven in the proper direction. To prevent lost motion and relieve the carriers of driving strain I provide each unit with a driving shaft 15 which is disposed longitudinally within the carrier, these driving shafts having gears 16 meshing with the beveled gears 17 on the shafts 9.

The shafts 15 are supported by the yoke-like members 18, the arms of which are mounted on the shafts 9 to embrace the gears 16 and 17.

The driving motor 20 is mounted on the truck 3 and is connected to one of the shafts 9 of the main section by the sprocket chain 21 and the sprockets 22 and 23. The shaft 24 on which the sprocket 23 is mounted is provided with beveled reversing gears 25 coacting with a gear 26 on the motor shaft.

With this arrangement of parts heavy loads may be conveyed with comparatively small motors, and the conveyer may be set up to meet particular conditions or requirements for loading or unloading both ends of a car.

I have illustrated an adaptation which I have found very satisfactory for the handling of cement and heavy objects. Various parts are shown mainly in conventional form as the structural details thereof may be greatly varied. I have not attempted to illustrate or describe certain modifications or adaptations which I contemplate as I believe the disclosure made will enable those skilled in the art to which my invention relates to embody or adapt the same as may be desired.

Having thus described my invention what I claim as new and desire to secure by Letters Patent is:

1. In a conveyer, the combination of a main unit and a plurality of supplementary units, each comprising side members, a carrier for each unit comprising shafts provided with sprocket wheels disposed between the side members, chains on said sprocket wheels provided with cross pieces, said shafts being arranged so that when said units are assembled end to end with the ends of the side pieces abutting the unit carriers are brought into coacting relation end to end, pinions on the ends of said carrier shafts, coacting idler pinions on the outer end of each unit adapted to mesh with the pinions on said shafts at the inner ends of the units when the units are in assembled relation, driving shafts disposed longitudinally of said conveyer units and provided with beveled gears at their ends, beveled gears on said carrier shafts meshing with said gears on said transmission shafts, supporting yokes for said driving shafts mounted on said carrier shafts to embrace said beveled gears, a truck on which said main unit is mounted, a motor on said truck, and driving connections for said motor and one of the carrier shafts of said main unit, said driving connections including a reversing means.

2. In a conveyer, the combination of a main unit and a plurality of supplementary units, each comprising side members, a carrier for each unit comprising shafts provided with sprocket wheels disposed between the side members, chains on said sprocket wheels provided with cross pieces, said shafts being arranged so that when said units are assembled end to end with the ends of the side pieces abutting the unit carriers are brought into coacting relation

end to end, pinions on the ends of said carrier shafts, coacting idler pinions on the outer end of each unit adapted to mesh with the pinions on said shafts at the inner ends of the units when the units are in assembled relation, driving shafts disposed longitudinally of said conveyer units within said carrier and provided with beveled gears at their ends, beveled gears on said carrier shafts meshing with said gears on said transmission shafts, and supporting yokes for said driving shafts mounted on said carrier shafts to embrace said beveled gears.

3. In a conveyer, the combination of a main unit and a plurality of supplementary units, each comprising side members, a carrier for each unit comprising shafts, oppositely disposed coacting coupling hooks disposed on the under sides of said unit side members to interlock when the side members are brought into abutting relation, pinions on the ends of said carrier shafts, coacting idler pinions on the outer end of each unit adapted to mesh with the pinions on said shafts at the inner ends of the units when the units are in assembled relation, driving shafts disposed longitudinally of said conveyer units and provided with beveled gears at their ends, beveled gears on said carrier shafts meshing with said gears on said transmission shafts, supporting yokes for said driving shafts mounted on said carrier shafts to embrace said beveled gears, a truck on which said main unit is mounted, a motor on said truck, and driving connections for said motor and one of the carrier shafts of said main unit, said driving connections including a reversing means.

4. In a conveyer, the combination of a main unit and a plurality of supplementary units, each comprising side members, a carrier for each unit comprising shafts, oppositely disposed coacting coupling hooks disposed on the under sides of said unit side members to interlock when the side members are brought into abutting relation, pinions on the ends of said carrier shafts, coacting idler pinions on the outer end of each unit adapted to mesh with the pinions on said shafts at the inner ends of the units when the units are in assembled relation, driving shafts disposed longitudinally of said conveyer units and provided with beveled gears at their ends, beveled gears on said carrier shafts meshing with said gears on said transmission shafts, and supporting yokes for said driving shafts mounted on said carrier shafts to embrace said beveled gears.

In witness whereof I have hereunto set my hand.

LEWIS D. NELSON.
